(57) **CLAIM**

The ornamental design for a video conference camera, as shown and described.

DESCRIPTION

FIG. 1 is a front perspective view of a video conference camera showing our new design;

FIG. 2 is a rear perspective view thereof;

FIG. 3 is another rear perspective view of the video conference camera shown with the camera rotated;

FIG. 4 is another front perspective view of the video conference camera shown with the camera tilted downwards;

FIG. 5 is another front perspective view of the video conference camera shown with the camera tilted upwards;

FIG. 6 is a top plan view of the video conference camera shown in FIG. 1;

FIG. 7 is a bottom plan view thereof;

FIG. 8 is a front elevation view thereof;

FIG. 9 is a rear elevation view thereof;

FIG. 10 is a left side elevation view thereof; and,

FIG. 11 is a right side elevation view thereof.

The broken lines shown in the drawings depict portions of the video conference camera that form no part of the claimed design.

1 Claim, 6 Drawing Sheets
